ATTORNEY

UNITED STATES PATENT OFFICE

THOMAS I. POTTER, OF PORTLAND, OREGON

COMPRESSOR

Application filed April 17, 1929. Serial No. 355,777.

This invention relates generally to compressors, and particularly to compressors such as are used in refrigerating systems, with special reference to compressors of the oscillating type.

The main object of this invention is to provide a compressor of the oscillating type having an improved form of port arrangement and adjustment therefor which will facilitate the manufacture of the compressor by eliminating unnecessary accuracy in the production of the parts, as well as providing a means for counteracting any natural accumulation of errors which are bound to arise in such manufacture.

The second object is to provide a special port arrangement whereby the ports of the compressor may be accurately positioned with reference to each other, and their relation to the cylinder itself may be made easily and accurately adjustable.

The third object is to so construct the compressor that the port action will be extremely rapid as to its closing and opening functions.

The fourth object is to provide a compressor whose clearance losses can be reduced to a minimum by constructing the cylinder with open ends, which also facilitates the manufacture thereof.

These, and other objects, will become more apparent from the specification following as illustrated in the accompanying drawings, in which:

Figure 1 is a vertical section through the compressor taken along the line 1—1 in Figure 2. Figure 2 is a transverse section through the compressor taken along the line 2—2 in Figure 1. Figure 3 is a side elevation of a port ring. Figure 4 is a plan of a port ring. Figure 5 is a bottom view of a port ring. Figure 6 is a diagrammatic view showing the piston in a straight line or dead center position. Figure 7 illustrates the piston in a discharge position. Figure 8 illustrates the piston in a suction position. Figure 9 illustrates a modified form of port opening used to facilitate the manufacture. Similar numbers of reference refer to similar parts.

Referring in detail to the drawings, the compressor consists of a pair of side frames 10

and 11 in which are formed the bearings 12 provided with the bushings 13 in which journals the crank shaft 14. The bearings 12 are in the uppermost portion of the side frames 10 and 11 and are provided with an oil reservoir 15 on the outer side thereof which are, of course, within the frames 10 and 11. The side frame 10 is provided with an opening 16 normally closed by a plug 17, by the removal of which access may be had to the slotted end 18 of the crank shaft 14 for the manual rotation thereof. The frame 11 is provided with an extension 19. At the outer end of the extension 19 is placed a cap 20 through which the shaft 14 passes and connects with the coupling 21, through which the necessary rotative power is transmitted.

A packing 22 (described in a co-pending application Serial No. 364,497) is placed against the inner side of the cap 20. The frames 10 and 11 are provided with feet 23 by means of which they may be mounted on a base 24 and held in position by the fastening bolts 25.

Between the frames 10 and 11 is placed a crank case or body of the compressor whose upper portion 26 is provided with fins 27 on its upper surface and whose lower portion 28 is provided with a cylindrical recess 29 in which is placed a pair of cylindrical port rings 30, each of which is provided with a slot 31 through which can freely pass the piston 32. The cylindrical port rings 30 are adjustably rotatable within the recess 29 and engage each other on adjacent faces 33. Each port ring 30 is provided with a pair of recesses 34 to receive the ends 35 of the tangential adjusting screws 36 which are threaded into the portions 37 of the crank case body. Within each port ring 30 is placed an oscillating cylinder 38 provided with a cylindrical opening 39 for the piston 32, and the transverse openings 40 which are used for preventing the building up of pressures between the cylinder elements 38. Each port ring 30 is provided with a curved exhaust port 41 and a curved intake port 42, and (as shown in Figure 6) when the piston 32 is on a dead center the edge of the exhaust port 41 coincides with the edge of the cylin- 100

der opening 39, while the edge of the intake port 42 is slightly removed therefrom.

The holes 41 and 42 may either be continuous (as shown in Figures 7 to 9) or may 5 consist of curved rows of holes 41-A and 42-A, which would be merely drilled instead of requiring a broaching operation where the ports are made continuous.

In the lowermost portion 43 of the crank 10 case body are formed the exhaust opening 44 and the suction opening 45 which are separated from each other by the wall 46. That portion of each port ring 30 which is always in contact with the face of the wall 15 46 is provided with an oil groove 47 which prevents the fluid being handled from being blown across a relatively narrow wall 46.

A cover plate 48 is placed over the openings 44 and 45 and held in position by means 20 of the screws 49. A suction duct 50 connects the opening 45 with the pipe 51 and an exhaust or outlet port 52 connects the opening 44 with the pipe 53.

It is a well known fact that the efficiency of 25 compressors of this type is dependent largely upon the accurate relation existing between the ports 41 and 42 and the opening 39. It has been the common practice in the past to form these ports in the body of the compressor 30 or itself, which might seem to be the logical position for same, but in actual practice there is usually an accumulation of errors in the component parts which, if not self-corrective, will cause a serious misplacement of the ports 35 with relation to their cylinder. These errors may occur in the formation of the ports themselves in their relation to each other, in the forming of the cylindrical opening 39 within the member 38, in the alignment of 40 the axis of the crank shaft 14 with relation to the axis of the recess 29, and in numerous other details either independently or in conjunction with each other, and in spite of the utmost care in the construction of such parts, 45 it was found extremely difficult to secure a right port action until they were made collectively adjustable with relation to their cylinders and the ports themselves were formed in an element whose nature made it possible 50 to accurately position these ports with relation to each other.

Obviously, when the compressor is assembled and the port rings 30 are adjusted to their best position, they are securely held in 55 place by the screws 36 and locked by means of the nuts 54.

I claim:

1. An oscillating compressor having a cylinder and an adjustable port ring in which 60 the cylinder of said compressor can oscillate.

2. In an oscillating compressor, the combination of a crank case, a crank shaft mounted in said case, a cylindrical port ring mounted 65 in said case having inlet and outlet ports

formed therein, means for rotatably adjusting said ring, a cylinder within said ring, and a piston within said cylinder operated by said crank shaft, said cylinder communicating alternately with said ports. 70

3. In an oscillating compressor, a rockable cylinder, a cylindrical plunger within said cylinder, a bearing for said cylinder having oppositely curved inlet and outlet ports formed therein to communicate alternately with the interior of said cylinder, and means for adjusting the relation between said ports and said cylinder. 75

4. In an oscillating compressor, a somewhat cylindrical crank case at the upper portion thereof, a cylindrical chamber formed in the lower portion thereof, a port ring in said cylindrical chamber, adjusting screws for rotatably adjusting said port ring, a pair of oppositely curved ports formed therein having independent intake and discharge connections separated by a wall between said ports, the outer area of said port ring between said ports having an oil groove 80 formed therein, a cylinder rockably mounted within said port ring, a plunger within said cylinder adapted to draw a fluid through one of said ports and force same out of the other port, a crank shaft in said crank case for operating said plunger and an oil chamber in the lower portion of said crank case whereby said cylinder can have its lower portion submerged in lubricant. 85

5. In an oscillating compressor the combination of a crank shaft, a rockable cylinder 90 whose axis is parallel to said crank shaft, a port ring in which said cylinder journals, a plunger in said cylinder actuated by said crank shaft, a support for said port ring, and means for adjusting the relation between 95 said port ring and a plane passing through the axes of said crank shaft and said port ring. 100

6. In an oscillating compressor the combination of a crank case, a crank shaft mounted in said case, an oscillating cylinder, a plunger within said cylinder operated by said crank, said crank case having inlet and outlet ports, and an adjustable member interposed between the oscillating cylinder and the crank case whereby a variable cut-off for the ports may be obtained. 110

7. In a compressor an oscillating cylinder open at both ends, one end having mounted therein a plunger and the other end forming the inlet and outlet opening for the cylinder, a bearing for said cylinder having formed therein a pair of oppositely disposed curved ports to register alternately with said cylinder during the course of its oscillations. 115

8. The combination of an oscillating cylinder having its pressure end completely open, and a bearing in which said cylinder can oscillate, said bearing having a pair of oppositely disposed arcuate ports formed 120

therein conforming to the sides of said cylinder and to register alternately therewith.

9. A compressor having a crank in the upper portion thereof and an oscillating cylinder in the lower portion thereof, said oscillating cylinder having a rotatably adjustable bearing, said bearing having a pair of oppositely curved spaced ports formed therein between which the end of the cylinder oscillates, and means for adjusting the relative overlap between said cylinder and ports.
